TAPE DECK COVER

Donald M. Spero, 1801 Clydesdale Place NW,
Washington, D.C. 20009

Filed July 9, 1971, Ser. No. 161,418

Term of patent 14 years

Int. Cl. D6—10

U.S. Cl. D21—6 R

FIG.1

FIG2

FIG3

FIG4

FIG. 1 is a plan view of a tape deck cover showing my new design;

FIG. 2 is a top plan view of the tape deck cover mounted on a tape deck shown in phantom for illustration purposes only;

FIG. 3 is a side view thereof; and

FIG. 4 is a front elevational view thereof.

I claim:

The ornamental design for a tape deck cover, substantially as shown and described.
